WINDOW FASTENER

Oscar P. Cadmus, Bayside, N. Y.

Application July 20, 1933, Serial No. 681,247

7 Claims. (Cl. 292—23)

This invention relates to improvements in window constructions and has for one of its objects to provide an improved window of simple and practical construction wherein a locking mechanism is provided which is operative to lock a window sash in any position of adjustment thereof.

Another object is to provide a novel form of locking mechanism and operating means therefor in which said mechanism includes a plurality of locking elements and a control member having relative movements therebetween for wedging said elements against the frame of the window and in which operating means is operable to release certain of said elements from locking contact with said frame as a sash therein is being raised or lowered.

The above and other objects will appear more clearly from the following detailed description when taken in connection with the accompanying drawings which illustrate a preferred embodiment of the inventive idea.

In the drawings:

Figure 1 is a front elevation of a window constructed in accordance with the present invention and of a type wherein the window space is adapted to be closed by a plurality of upper and lower sashes.

Figure 2 is a fragmentary vertical longitudinal section through the window frame and one set of upper and lower sashes.

Figure 3 is a fragmentary horizontal section through the window construction shown in Figure 1.

Figure 4 is a fragmentary vertical section through the lower sash illustrating the locking mechanism of the present invention in the normal locking position that it assumes after the sash has been adjusted to either closed, fully opened, or partially opened positions.

Figure 4a is a fragmentary vertical section of a portion of the mechanism which forms a continuation of the upper end of the vertical side of the sash down in Figure 4.

Figure 5 is a view similar to Figure 4 illustrating the lower locking element in its released position which is assumed as the sash is being lowered.

Figure 6 is an edge elevation of the sash showing the lower locking element in the position of Figure 4.

Figure 7 is a view similar to Figure 6 showing said locking element actuated by the operating member to a released position as in Figure 5, and

Figure 8 is an enlarged transverse section on the line 8—8 of Figure 4.

The window of the present invention is preferably of the type constructed entirely of non-rusting metal and the various elements thereof are of such design that the sashes and frame may be adapted to all kinds of buildings and their shapes and sizes altered to suit any specified condition. As shown in Figures 1 to 3, the window is of the type comprising vertical series of upper and lower sashes 10 and 11, there being three of such series shown in Figure 1 with mullions 12 interposed between adjacent vertical edges of the pairs of sashes to provide guides therefor. It will be understood, of course, that other types of windows may be employed, such as those including but one upper and one lower sash, without materially altering the locking mechanism of the present invention or departing from the scope thereof. It will be further understood that when series of sashes such as shown in Figures 1 and 3 are employed, a locking mechanism illustrated in detail on the other figures of the drawings is utilized with each one of the sashes, the mechanism for each upper sash being inverted from the position shown in Figure 4 wherein the mechanism is illustrated in connection with a lower sash in which the window opening, including the head 13 sill 14 and the vertical side jambs 15, is lined by the metallic substantially rectangular frame, generally indicated by the numeral 16, having vertically offset channels therein formed by a series of guide strips 17 which are adapted to receive the upper and lower sashes 10 and 11. Each of the sashes comprises a hollow metallic framework consisting of vertical sides 18 adapted to slide in channels formed by the guide strips 17, the meeting rails 19, the bottom rail 20 of the lower sash, and the top rail 21 of the upper sash. The locking mechanism of the present invention will be described in detail in connection with one of the lower sashes 11 such as illustrated in Figures 4 and 4a and, as previously indicated, this locking mechanism is duplicated in each of the upper sashes 10 except that it is located in an inverted position from that assumed in the lower sash.

The locking mechanism is preferably contained within the sides 18 and bottom rail 20 of the lower sash and, as shown in Figures 4 and 4a, comprises a lock control element generally indicated by the numeral 22 positioned within each of the sides 18 of the sash and consisting of an elongated strip which is secured to the inner wall of said side by suitable fasteners such as the

screws 23. The element 22 further comprises the spaced upper and lower projecting portions 24 and 25, respectively, having the effective surfaces 26 and 27 thereof inclined in opposite directions. 5 These surfaces combine with the outer wall 28 of the side 18 to form wedge-shape recesses adapted to receive therein the upper and lower locking elements 29 and 30. These elements may take the form of either ball or roller bearings 10 which are yieldably supported in their respective recesses by means of steel or hard bronze coil springs 31 carried by the upper and lower ends of the respective portions 24 and 25. The upper locking element 29 is adapted to be projected by 15 its associated spring 31 through an elongated opening 32 formed in the outer wall 28 of the side 18 opposite the inclined surface 26, so that said locking element will engage the stile 33 of the frame 16 and thereby become wedged between 20 said surface 26 and the stile so as to lock the sash 11 against upward movement when an attempt is made to raise the sash by any other means than the operating member to be presently described. Likewise, the lower locking element 30 is projected through an elongated opening 34 in the wall 28 so that it will be wedged between the surface 27 and the stile 33 to lock the sash against 25 downward movement. Thus the locking elements 29 and 30 will cooperate to lock the sash 11 in any position of adjustment thereof and will maintain said sash in such position until one or the other locking elements is positively actuated, by 30 the operating member presently to be described, to recede within its recess against the action of the associated spring 31. If the adjustment of the sash to be made is in an upward direction the locking element 29 is positively forced into its recess formed by the inclined surface 26, whereas if the adjustment is downward the locking element 30 is forced downwardly into its recess. During an upward adjustment of the sash, the contact of the element 30 with the stile 33 will produce sufficient friction to cause said element to move downwardly into its recess formed by 35 the surface 27 against the tension of the spring 31, while during a downward adjustment of the sash the element 29 will likewise be caused to moved into its recess so that neither of said elements will interfere with the easy sliding movement of the sash if the other element has been 40 positively actuated by the operating member.

The operating means for the locking elements 29 and 30 of the lower sash 11 preferably comprises a U-shaped operating member generally indicated by the numeral 35 which is located 45 within said sash and which consists of the single horizontal channel bar 36 extending through the bottom rail 20, and the two vertical channel bars 37 each of which extends longitudinally of one 50 of the sides 18 of the sash in cooperation with the locking means in said sides. At spaced points along the intermediate wall of each bar 37, which wall engages the interior surface of the outer wall 28 of the side 18, said intermediate wall is provided with elongated upper and lower slots 38 and 39 which are in registration with the openings 55 32 and 34, respectively, in the outer wall 28 so that the locking elements 29 and 30 will project through said slots. In the normal position of the operating member 35, shown in Figure 4, the horizontal bar 36 thereof is situated medially of the upper and lower edges of the rail 20, the lower end of the upper slot 38 is located adjacent the locking element 29, and the upper end of the 60 slot 39 is spaced slightly from the locking ele-

ment 30. Intermediate the ends of the bottom rail 20 of the sash the interior side thereof is provided with a vertically disposed slot 40 and in alignment with said slot the bar 36 of the operating member carries a block or enlargement 41 to 5 which a handle 42 is secured by means of a screw 43, said handle being utilized to manipulate the operating member 35 when raising or lowering the sash. The normal or intermediate position of the operating member 35 is maintained by the provision of a coil spring 44 located within each of the sides 18 and interposed, as shown in Figure 4a, between the upper end of the upper portion 24 of the element 22 and an inturned flange 45 at the upper end of the vertical bar 37. 15

In practice, should it be desired to lower the sash 11 from a fully or partially opened position, the handle 42 is grasped and forced downwardly, the initial movement of this handle being relative to the rail 20 owing to the slot 40 therein, 20 and this initial movement is utilized to accomplish the release of the locking elements 30 in the vertical sides 18 of the sash. Thus as the handle is moved downwardly a like movement is imparted to the operating member 35 and just 25 before the portion of the handle projecting through the slot 40 reaches the bottom of the latter the upper end of the slot 39 in each bar 37 will contact its associated locking element 30, as 30 illustrated in Figures 5 and 7. Thereafter a continued downward movement of said operating member will cause said locking element to recede within its recess against the action of its associated spring 31 so that said locking element will 35 no longer cause a wedging action to be produced between the inclined surface 27 and the stile 33. At the same time, the downward movement of the sash relative to the stile 33 permits the latter, by reason of its contact with the locking element 29 to force said element inwardly into its recess so 40 that no binding action will occur at this point. When the locking elements 29 and 30 have thus been released, the latter by the positive action of the bar 37, and the handle 42 has reached the bottom of the slot 40, further downward pressure 45 upon said handle will now move the sash in the desired direction. During this movement the spring 44 has been compressed by reason of the downward pressure of the flange 45 thereagainst and as a consequence, when the desired position 50 of the sash has been attained and the handle 42 released, the spring 44 will expand and thereby cause a lifting action upon the operating member 35 until it has been restored to its normal intermediate position. When this occurs the upper end of the slot 39 has been moved away from the locking element 30, whereupon the associated spring 31 will again force said element upwardly and outwardly into locking or wedging engagement with the stile 33. In a like manner when 60 it is desired to raise the sash 11, a lifting action upon the handle 42 will cause the lower end of the slot 38 in each of the bars 37 to raise the associated locking element 29 against the action of its spring so that said element will recede into 65 its recess and at the same time the locking element 30 will move slightly into its recess by reason of the frictional contact thereof with the stile 33. After the release of said locking elements has been so effected, the portion of the 70 handle extended through the slot 40 will engage the upper end of the latter and continued upward pressure will then raise the sash to the desired position. Upon release of the handle, the operating member 35 will drop of its own weight 75

until the flanges 45 again contact the upper ends of the springs 44 which thereupon act to center bar 36 of the operating member within the rail 20.

As previously explained the locking mechanism just described is duplicated in each of the upper sashes 10 but in an inverted position and is operated, in a manner which will be clear from the foregoing description, by means of handles 46 carried by the upper rails 21 of the upper sashes.

10 A weather-proofing strip 47 (Figure 2) may be secured to the meeting rail 19 of the lower sash and overlap the space between said meeting rails and a similar weather strip 48 may depend from the exterior surface of the bottom rail 20 so as 15 to overlap a part of the sill portion of the frame 16.

What is claimed is:

1. A lock mechanism for windows comprising a lock control element adapted to be mounted in each side of a window sash and having upper and lower surfaces inclined in opposite directions from each other, a lock element associated with each surface and wedged thereby against a window frame to prevent movement of the sash in one direction, and means to move said locking element out of wedging engagement with said frame and to also adjust the sash in said direction.

2. A lock mechanism for windows comprising a lock control element adapted to be mounted in each side of a window sash, upper and lower locking elements associated with said control element and having engagement with a window frame to lock the sash in any position of adjustment, and a U-shaped operating member adapted to be mounted entirely within and have movement relative to said sash, said member having contact with certain of said locking elements to shift the latter out of locking contact with said frame as the sash is raised or lowered.

3. A lock mechanism for windows comprising a lock control element adapted to be mounted in the side of a window sash and having inclined surfaces extending in opposite directions to each other, a spring-pressed locking element engaged with each inclined surface and adapted for projection through the sash for locking contact with a window frame, and means to move certain of said locking elements out of locking contact with said frame while the other locking elements remain in contact therewith, when said sash is being raised or lowered.

4. A lock mechanism for windows comprising a lock control element adapted to be mounted in each of the sides of a window sash and having inclined surfaces extending in opposite directions to each other, a spring-pressed locking element engaged with each inclined surface and adapted for projection through said sash for locking contact with a window frame, and an operating member adapted for disposition in said sash and having side portions extending into the sides of said sash, said side portions having slots the ends of which are disposed so as to contact adjacent

locking elements when said operating member is actuated to thereby shift the contacted locking elements out of locking contact with said frame.

5. A lock mechanism for windows comprising locking elements adapted to be carried by a window sash on opposite sides thereof for engagement with a window frame to lock the sash in any position of adjustment thereof, and a lock operating member having one portion thereof disposed within and coextensive with an end rail 10 of said sash and other portions in the sides thereof, said operating member having initial movements in opposite directions relative to said sash either of which movements effects engagement of said other portions of the operating 15 member with certain of said locking elements to move the latter out of locking contact with said frame, and means carried by the first-named portion of said operating member and engaged with said end rail, at the termination 20 of either of said initial movements, to raise or lower said sash by a continued movement of said operating member in the same direction as the initial movement thereof.

6. A lock mechanism for windows comprising 25 locking elements adapted to be carried by a window sash on opposite sides thereof for engagement with a window frame to lock the sash in any position of adjustment thereof, a lock 30 operating member having one portion thereof disposed within and coextensive with an end rail of said sash and other portions in the sides thereof, said operating member having initial movements in opposite directions relative to said sash either of which movements effects engagement of said other portions of the operating 35 member with certain of said locking elements to move the latter out of locking contact with said frame, and a handle for said operating member connected thereto through said sash and 40 operable upon a continued movement of said operating member in either of said different directions to engage said sash and adjust the same in the direction of said movement.

7. A lock mechanism for windows comprising 45 locking elements adapted to be disposed within the sides of a window sash and to project there-through for engagement with a window frame to lock the sash in any position of adjustment thereof, a U-shaped operating member movable 50 in different directions within said sash and having portions engageable with certain of said locking elements in either direction of movement of said member to shift the latter elements out of locking contact with said frame, and a handle 55 for adjusting said sash connected to said operating member through an end rail of the sash and operable, subsequent to the shifting of said latter locking elements, by a continued movement in the same direction in which said operating member is initially moved, to engage said end rail to raise or lower said sash.

OSCAR P. CADMUS.
